US00D865760S

(12) **United States Design Patent** (10) Patent No.: **US D865,760 S**
Beristain et al. (45) Date of Patent: **** Nov. 5, 2019**

(54) **WEARABLE TRACKER**

(71) Applicant: **Festiie, Inc.**, Los Angeles, CA (US)

(72) Inventors: **Desmond Anthony Beristain**, Los Angeles, CA (US); **Daniel Neema Salehi**, Los Angeles, CA (US)

(**) Term: **15 Years**

(21) Appl. No.: **29/653,125**

(22) Filed: **Jun. 12, 2018**

(51) LOC (12) Cl. **14-02**

(52) U.S. Cl.
